(57) CLAIM

The ornamental design for a set of modular cushions, as shown and described.

DESCRIPTION

FIG. 1 is a perspective view of a first, a second, and a third embodiment of a set of modular cushions in an assembled configuration, showing our new design, consisting of a top cushion, a base cushion, and one interior cushion; FIG. 2 is a top plan view thereof;

FIG. 3 is a bottom plan view thereof, showing the base cushion and an interior cushion;

FIG. 4 is a left side elevation view thereof, with the front, right side, and rear elevation views being identical thereto;

FIG. 5 is a perspective view of the base cushion of the set of modular cushions, shown separately to reveal aspects of the design that would not otherwise be apparent in the assembled view;

FIG. 6 is a top plan view thereof, with the bottom plan view being identical thereto;

FIG. 7 is a left side elevation view thereof, with the front, right side, and rear elevation views being identical thereto;

FIG. 8 is a perspective view of the top cushion of the set of modular cushions, shown separately for ease of illustration; FIG. 9 is a top plan view thereof, with the bottom plan view being identical thereto;

FIG. 10 is a left side elevation view thereof, with the front, right side, and rear elevation views being identical thereto;

FIG. 11 is an enlarged perspective view of an interior cushion of the first embodiment of the set of modular cushions, shown separately to reveal aspects of the design that would not otherwise be apparent in the assembled view; FIG. 12 is a top view thereof, with the bottom plan view being identical thereto;

FIG. 13 is a left side elevation view thereof, with the front, right side, and rear elevation views being identical thereto;

FIG. 14 is an exploded perspective view of the first embodiment of the set of modular cushions in a disassembled configuration;

FIG. 15 is an enlarged perspective view of an interior cushion of the second embodiment of the set of modular cushions, shown separately to reveal aspects of the design that would not otherwise be apparent in the assembled view; FIG. 16 is a top view thereof, with the bottom plan view being identical thereto; FIG. 17 is a left side elevation view thereof, with the front, right side, and rear elevation views being identical thereto; FIG. 18 is an exploded perspective view of the second embodiment of the set of modular cushions in a disassembled configuration; FIG. 19 is an enlarged perspective view of an interior cushion of the third embodiment of the set of modular cushions, shown separately to reveal aspects of the design that would not otherwise be apparent in the assembled view; FIG. 20 is a top view thereof, with the bottom plan view being identical thereto; FIG. 21 is a left side elevation view thereof, with the front, right side, and rear elevation views being identical thereto; and, FIG. 22 is an exploded perspective view of the third embodiment of the set of modular cushions in a disassembled configuration. The long dash-short dash broken lines depict the assembly of the set of modular cushions and form no part of the claimed design. The even long dash-dash broken lines depict environmental subject matter of the set of modular cushions and form no part of the claimed design.
